Geo. P. Kimmel.

ATTORNEY.

UNITED STATES PATENT OFFICE

LOUIS RAYMOND ZEHNDER, OF LOUISVILLE, KENTUCKY, ASSIGNOR, BY MESNE ASSIGNMENTS, TO LOUISVILLE FROG, SWITCH & SIGNAL COMPANY, OF LOUISVILLE, KENTUCKY, A CORPORATION

REFLECTING DEVICE

Application filed May 11, 1928. Serial No. 276,997.

This invention relates to a lens cap, holder or carrier for use in connection with reflector devices of that type whereby incidental light is reflected so as to illuminate advertising signs, signals and the like, and the invention has for its object to provide, in a manner as hereinafter set forth, a lens cap, holder or carrier forming one of the elements of and arranged relative to the other elements of a reflecting device for securing the elements of the latter together to provide a unit, and further with the cap, holder or carrier serving as a means for securing the unit to the object in which it is to be placed, that is the base of the sign or signal.

A further object of the invention is to provide, in a manner as hereinafter set forth, a lens cap, holder or carrier for a reflecting device in a manner whereby a reflector and a large part of the lens forming elements of the reflector device are closed.

Further objects of the invention are to provide, in a manner as hereinafter set forth, a lens cap, holder or carrier for a reflecting device which is simple in its construction and arrangement, strong, durable, compact, thoroughly efficient in its use, conveniently united with a lens to enclose a large part thereof, and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 illustrates in vertical section a lens cap, holder or carrier in accordance with this invention and further showing the adaptation thereof with respect to a lens and reflector and further with the reflecting unit mounted in the base of a sign or signal.

Figure 2 is a top plan view of the form shown in Figure 1.

Figure 3 illustrates in vertical section a modified form of lens cap, holder or carrier showing the adaptation thereof with respect to a lens, reflector and the base of a sign or support.

Figure 4 is a top plan view of the structure shown in Figure 3.

Figures 5, 6 and 7 are vertical section views of modified forms of lenses.

The lens cap, holder or carrier will be hereinafter termed a holder.

The lens as illustrated in connection with each holder is generally designated at 20 and comprises a cylindrical body portion 21 of uniform cross section and a pair of end portions 22, 23 of convex curvature. The body portion 21 is of materially greater length than the combined length of the end portions 22, 23. The lens is bi-convex.

Each of the holders as shown is of less length than the length of the lens and is formed with a convex bottom or inner end and with the latter closed. A reflector conforms in contour to the inner face of the bottom or inner end of the holder and the reflector can be set up in any suitable manner and preferably the inner face of the inner end or closed bottom of each holder can be silvered or formed in any suitable manner to provide the reflector and which is designated 70 with respect to each form of holder illustrated.

Referring to Figures 1 and 2 of the drawings the holder comprises a cylindrical body portion 25 open at its outer end and having a closed, convexed inner end or bottom 26. The body portion 25 in proximity to its open end is formed with a laterally extending annular flange 27 which merges into an annular portion 28. That part of the body portion 25 extending inwardly from the flange 27 to the inner end 26 is of an inner diameter to snugly fit the body portion 21 of the lens 20. The portion 28 is offset relative to that part of the body portion 25 extending inwardly from the flange 27. The portion 28 is disposed in a plane disposed concentric to the remaining part of the body portion 25.

In Figure 1, 31 indicates the base of a sign or signal and which is formed with a socket

55

32 of uniform diameter throughout. The offset annular portion 28 has its forward edge flush with the outer face of the base 31 and its outer diameter is the same as the diameter 5 of the socket so as to frictionally engage the wall of the socket and secure the unit therein. The diameter of that part of the body portion 25 of the holder which extends inwardly from flange 27 is materially less than the 10 diameter of the socket whereby such part is spaced from the wall of the socket 32.

The lens 20 is of greater length than the length of the holder and the convexed end 23 of the lens 20 snugly seats against the reflector 24. The body portion 21 of the lens 15 20 projects beyond the flange 29.

The flange 27, in connection with the annular portion 28 and body portion 21 of the lens 20 provides a pocket for a securing and sealing medium 35. The holder provides 20 means for securing the reflector 24 and lens 20 together to provide a unit. The sealing material or medium secures the holder to the lens 20 and possesses a characteristic which 25 will prevent moisture or foreign matter from getting in contact with the reflector 24 so as not to destroy its reflecting function.

The form illustrated in Figures 3 and 4 is of the same construction as that shown in 30 Figure 1 and the holder is generally indicated at 36 and has the offset annular portion 37 thereof serrated or toothed upon its outer periphery as indicated at 38 providing means for securing the holder in position with respect to the base 39. The knurled, serrated or toothed annular portion 36 allows for the 35 holder to be driven in sockets varying somewhat in size without crushing the sealing medium.

In Figures 5, 6 and 7 there is shown 40 different shapes of lenses and shown in Figure 5 the lens is of plano-convex contour. In Figure 6 the lens shown is of bi-convex contour and in Figure 7 of convex-concave contour. The lens in Figure 5 is indicated at 40. That in Figure 6 at 41 and the lens in Figure 7 at 42. Preferably a bi-convex lens will be employed with the holder, but it is to be understood that the forms shown in Figures 5 45 and 7 can be employed in the unit and the latter will consist of a holder, a reflector, a lens and a sealing medium. The holder will be of a length to have its inner end seat against the bottom of the socket. The combined sealing and securing medium is indicated, where it is shown at 35.

When the elements of the unit are arranged 50 together a part of the body portion 21 of each lens projects from the outer end of the holder. The inner end of a bi-convex lens is to rest against the reflector 24, and the latter is to conform to the shape of such inner end and such shape will conform to that of the bottom or inner end of the holder.

55 The reflecting unit is commonly used in

the construction of road indicators and other signs which at night are illuminated or rendered visible by the reflection of light coming from the lamps of motor vehicles or some other extraneous source. The units can be 70 arranged in any manner desired. Although the unit is designed primarily for road indicators and other signs, yet it is to be understood that it can be employed for forming symbols, letters, figures and also in connection with buoys or for any other purposes 75 for which it is found applicable.

It is thought the many advantages of a reflecting device or unit in accordance with this invention, more particularly the lens 80 holder forming an element thereof, can be readily understood, and although the preferred embodiment of the invention is as illustrated and described, yet it is to be understood that changes in the details of construction 85 can be had which fall within the scope of the invention as claimed.

What I claim is:

1. In a reflecting device a lens holder comprising a hollow, cylindrical body having a closed inner end and an open outer end, said body including an inner part and an outer part for surrounding the lens, the inner diameter of said inner part being such to provide for the latter to snugly fit the lens, said outer part offset with respect to and being connected at its inner end to the outer end of said inner part and providing in connection with the lens a pocket for the reception of a means for connecting the lens to said body and for sealing 90 said inner part.

2. In a reflecting device a lens holder comprising a hollow body having a closed inner end and an open outer end, said body including an inner part and an outer part for surrounding the lens, said outer part offset with respect to and connected with said inner part and providing in connection with the lens a pocket for the reception of a means for connecting the lens to said body and for sealing 95 said inner part, the closed inner end of said body conforming in contour to the shape of the inner end of the lens and having its inner face provided with a reflecting means.

3. In a reflecting device a lens holder comprising a hollow body having a closed inner end and an open outer end, said body including an inner part and an outer part for surrounding the lens, said outer part offset with respect to and connected with said inner part and providing in connection with the lens a pocket for the reception of a means for connecting the lens to said body and for sealing 110 said inner part, the closed inner end of said body being of convex contour and having its inner face provided with a reflecting means.

4. In a reflecting device a lens holder comprising a hollow, cylindrical body having a closed inner end and an open outer end, said body including an inner part and an outer 115

part for surrounding the lens, the inner diameter of said inner part being such to provide for the latter to snugly fit the lens, said outer part offset with respect to and being connected at its inner end to the outer end of said inner part and providing in connection with the lens a pocket for the reception of a means for connecting the lens to said body and for sealing said inner part, said outer part being of materially less length than said inner part.

10 5. In a reflecting device a lens holder comprising a hollow, cylindrical body having a closed inner end and an open outer end, said body including an inner part and an outer part for surrounding the lens, the inner diameter of said inner part being such to provide for the latter to snugly fit the lens, said outer part offset with respect to and being connected at its inner end to the outer end of said inner part and providing in connection with the lens a pocket for the reception of a means for connecting the lens to said body and for sealing said inner part, said body of less length than the length of the lens and said outer part being of less length than the length of said inner part.

6. In a reflecting device a lens holder comprising a hollow, cylindrical body portion having a closed inner end and an open outer end, said body formed at a point between its transverse median and its outer end with a laterally extending flange thereby providing the outer part of the body offset with respect to the inner part thereof, the said outer part of said body in connection with the lens providing a pocket for the reception of a means for connecting the lens to said body and for sealing the inner part of the latter, and the inner diameter of said inner part being such to provide for the latter to snugly fit the lens.

40 7. In a reflecting device a lens holder comprising a hollow body portion having a closed inner end and an open outer end, said body formed at a point between its transverse
45 median and its outer end with a laterally extending flange thereby providing the outer part of the body offset with respect to the inner part thereof, the said outer part of said body in connection with the lens providing
50 a pocket for the reception of a means for connecting the lens to said body and for sealing the inner part of the latter, and said body having its closed end of convex contour, the closed end of said body having its inner face
55 provided with a reflecting means.

3. provided with a reflecting means.

8. In a reflecting device a lens holder of less length than the lens mounted therein, said lens holder including a hollow body portion having a closed inner end and an open outer end, said body having a part thereof for snug engagement with a part of the lens, the other part of said body offset with respect to the lens and providing in connection therewith a pocket for the reception of a means for connecting the lens to said body and for seal-

ing that part of the body which snugly engages the lens.

9. In a reflecting device a lens holder of less length than the lens mounted therein, said lens holder including a hollow body portion having a closed inner end and an open outer end, said body having a part thereof for snug engagement with a part of the lens, the other part of said body offset with respect to the lens and providing in connection therewith a pocket for the reception of a means for connecting the lens to said body and for sealing that part of the body which snugly engages the lens, the closed inner end of said body being of convex contour and having its inner face provided with a reflecting means. 70 75 80

10. In a reflecting device a lens holder of less length than the lens mounted therein, said lens holder including a hollow body portion having a closed inner end and an open outer end, said body having a part thereof for snug engagement with a part of the lens, the other part of said body offset with respect to the lens and providing in connection therewith a pocket for the reception of a means for connecting the lens to said body and for sealing that part of the body which snugly engages the lens, the closed inner end of said body being of convex contour and having its inner face provided with a reflecting means, that part of said body for snug engagement with the lens being of materially greater length than that part of said body offset with respect to the lens. 85 90 95

11. In a reflecting device a lens holder of 100
less length than the lens mounted therein,
said lens holder including a hollow body por-
tion having a closed inner end and an open
outer end, said body having a part thereof
for snug engagement with a part of the lens,
the other part of said body offset with re-
spect to the lens and providing in connection
therewith a pocket for the reception of a
means for connecting the lens to said body
and for sealing that part of the body which
snugly engages the lens, the closed inner end
of said body being of convex contour and
having its inner face provided with a re-
flecting means conforming in contour to and
adapted to abut throughout the inner end of
the lens, that part of said body for snug en-
gagement with the lens being of materially
greater length than that part of said body
offset with respect to the lens. 105
110
115

12. In a reflecting device a lens holder comprising a hollow, cylindrical body having a closed inner end and an open outer end, said body including an inner part and an outer part for surrounding the lens, said outer part offset with respect to and being connected at its inner end with the outer end of said inner part and providing in connection with the lens a pocket for the reception of a means for connecting the lens to said body and for sealing said inner part, and said offset part 120
125
130

having inherent means on the outer periphery thereof for securing holder in position.

13. In a reflecting device a lens holder comprising a hollow body having a closed inner end and an open outer end, said body including an inner part and an outer part for surrounding the lens, said outer part offset with respect to and connected with said inner part and providing in connection with the lens a pocket for the reception of a means for connecting the lens to said body and for sealing said inner part, the closed inner end of said body conforming in contour to the shape of the inner end of the lens and having its inner face provided with a reflecting means, and said offset part having inherent means on the outer periphery thereof for securing holder in position.

14. In a reflecting device a lens holder of less length than the lens mounted therein, said lens holder including a hollow body portion having a closed inner end and an open outer end, said body having a part thereof for snug engagement with a part of the lens, the other part of said body offset with respect to the lens and providing in connection therewith a pocket for the reception of a means for connecting the lens to said body and for sealing that part of the body which snugly engages the lens, the closed inner end of said body being of convex contour and having its inner face provided with a reflecting means, that part of said body for snug engagement with the lens being of materially greater length than that part of said body offset with respect to the lens, and said offset part having inherent means on the outer periphery thereof for securing holder in position.

40 15. In a reflecting device a lens holder of less length than the lens mounted therein, said lens holder including a hollow body portion having a closed inner end and an open outer end, said body having a part thereof for snug engagement with a part of the lens, the other part of said body offset with respect to the lens and providing in connection therewith a pocket for the reception of a means for connecting the lens to said body and for sealing that part of the body which snugly engages the lens, the closed inner end of said body being of convex contour and having its inner face provided with a reflecting means conforming in contour to and adapted to abut throughout the inner end of the lens, that part of said body for snug engagement with the lens being of materially greater length than that part of said body offset with respect to the lens, and said offset part having inherent means on the outer periphery thereof for securing holder in position.

60 16. In a reflecting device a lens holder comprising a hollow body having a closed inner end and an open outer end, said body includ-

ing an inner part and an outer part for surrounding the lens, the inner diameter of said inner part being such to provide for the latter to snugly fit the lens, said outer part offset with respect to and being connected at its inner end to the outer end of said inner part and providing in connection with the lens a pocket for the reception of a means for connecting the lens to said body and for sealing said inner part, said holder for positioning in a socket of uniform diameter, and the outer diameter of said offset portion being such to provide for the latter to frictionally engage the wall of such socket to secure the holder in position

70 17. In a reflecting device a lens holder comprising a hollow body having a closed inner end and an open outer end, said body including an inner part and an outer part for surrounding the lens, said outer part offset with respect to and connected with said inner part and providing in connection with the lens a pocket for the reception of a means for connecting the lens to said body and for sealing said inner part, the closed inner end of said body conforming in contour to the shape of the inner end of the lens and having its inner face provided with a reflecting means, said holder for positioning in a socket of uniform diameter, and the outer diameter of said offset portion conforming in diameter to that of said socket to frictionally engage the wall of the latter to secure the holder in position.

80 18. In a reflecting device, a lens holder comprising a hollow body having a closed inner end and an open outer end, said body including an inner part and an outer part for surrounding the lens, said outer part offset with respect to and connected to said inner part and providing in connection with the lens a pocket for the reception of a means for connecting the lens to said body and for sealing said inner part, and said outer part having lengthwise extending, inherent means on the outer periphery thereof for securing said holder to a support therefor.

In testimony whereof, I affix my signature hereto.

LOUIS RAYMOND ZEHNDER.
